UNITED STATES PATENT OFFICE.

EDWARD H. MERSMAN, OF CELINA, OHIO.

EXTENSION-TABLE.

1,109,243.

Specification of Letters Patent.

Patented Sept. 1, 1914.

Application filed August 7, 1911. Serial No. 642,699.

To all whom it may concern:

Be it known that I, EDWARD H. MERSMAN, a citizen of the United States, residing at Celina, in the county of Mercer and State 5 of Ohio, have invented certain new and useful Improvements in Extension-Tables, of which the following is a specification.

My invention relates to improvements in extension tables, and more particularly to extension tables wherein the extension is effected through the agency of a leaf permanently associated with the table structure, and arranged to be hidden from view when the table is closed.

One of the particular objects of my invention is to provide a construction whereby round tables, and tables having a rim set in somewhat from the edge of the table top, may be equipped with such a folding leaf.

In the drawing, wherein I have illustrated an embodiment of my invention, Figure 1 is a bottom plan view, with parts in section, showing a round, rimmed, table equipped with my invention, in closed position; Fig. 2 is a cross section on line 2—2 of Fig. 1; Fig. 3 is a cross section on line 3—3 of Fig. 1; Fig. 4 is a view similar to Fig. 1, showing the table in opened position; and Fig. 5 is a section on line 5—5 of Fig. 4.

In the drawings, 10 and 10^a indicate table-top sections, herein shown as of a round table, provided with a decorative rim 11, set in from the edge on the underside of the top.

12 indicates a pedestal of any suitable construction, herein shown as a non-dividing pedestal, supporting the usual bridge cap 13. The middle pair of slides 14 are secured, as at 15, to the bridge in usual fashion and coöperate with the inner slide pair 16 and the outer slide pair 16^a in usual fashion. The slides 16 and 16^a are secured to their respective table-top sections 10 and 10^a in such fashion as to leave a clearance space of suitable depth between the central portion of the table-top sections and the tops of the slides for the reception of the concealable leaf to be described. To this end, blocks 50 17 and 17^a are interposed between the slide members 16 and 16^a and the respective table-top sections, 10 and 10^a, the slides being secured to the table-top sections, through said interposed blocks, only at their outer extremities, as indicated at 18, such fastenings being shown throughout as screws for

purposes of clear illustration. The bridge cap 13 also has secured thereto, as at 19, just inside of the slide, a pair of frame strips 20 which at one end are spanned by a cross beam 21.

The concealable leaf 25 has a central body portion of such dimensions that it fits easily in the space between blocks 17 and 17^a when the table is closed, lying wholly within the rim 11 of the table. To its longitudinal side edges (parallel with the slides) are pivotally secured edge plates 26. The pivotal connection between the edge plates or sections and the body of the leaf are preferably made through spring hinges 27, of well known construction, which tend to hold the edge plates in horizontal alinement with the leaf-body. The co-acting edges of the edge plates and body may be correspondingly tongued and grooved to increase the strength of the joint and insure fitting of the parts. The edge members 26 carry rim sections 11' and provision conveniently may be made for latching each edge member in depressed or retracted position by mounting on the under side of the body 25 a spring latch 29, of any ordinary, well-known construction, to coöperate with clip 30 on the rim section 11', as shown in Fig. 2.

Upon the under side of the leaf body 25, just inside of the frame members 20, I secure, as at 31, strips 32; and connect the strips 32 to the frame members 20 by parallel swinging links 33, each arranged in a triangular recess 34 in the frame strip 20. For raising and lowering the leaf on these swinging link members, I provide a suitable oscillating handle 36 upon the cross beam 21 of the frame members 20, and connect it by a distance-rod 37, with the leaf, the operating oscillator 36 being preferably of well known construction, arranged to throw the end of the rod 37 attached thereto past dead center for toggle locking 100 action when the handle is operated to elevate the leaf. Suitable dowels 38 are provided for effecting connection between the edges of the leaf body and the edge members, and the adjoining table-top sections.

In operation, when it is desired to extend the table, the table-top sections are pulled apart, their slide members 16 and 16^a sliding in the slide member 14 attached to the pedestal, and leaving between the table-top 110 sections a space somewhat wider than the leaf 25. The edge members of the leaf are

unlatched to horizontal position, where they are held by the spring hinge. The handle 36 is then oscillated to throw the leaf forward and upward, raising it to the level of 5 the table-top sections, and then, when the table-top sections are pushed together, the dowels effect rigid connection between all parts of the enlarged top.

For reduction of the size of the table, the 10 operation is reversed, the table-top sections being pushed open sufficiently to give the necessary clearance, the operating handle 36 reversely moved to drop the leaf into its lowest position where it stands in the space 15 between the plane of the slide 14 and the plane of the table top section, the edge members 26 of the leaf being then forced to depressed position and there latched, and the table-top sections then being moved to closed 20 position to overlie and completely conceal the leaf. It will be observed that when the table is closed, the leaf with its edges infolded is completely contained within the smaller circle of the rim 11, but that when open 25 and raised it fills out the full width of the table, and provides a continuation of the rim.

While I have herein described in some detail a particular embodiment of my invention, it will be apparent to those skilled in the art that changes in the details thereof might be made without departure from the spirit of my invention and within the scope of the appended claims.

35 5. What I claim is:

1. In an extension table, the combination of a set of three slide pairs; a bridge connecting the central pair of slides; top sections carried by the inner and outer slide 40 pairs, adapted to meet when the table is closed, and mounted above their slides to leave a central clearance space between the slides and top sections; a leaf adapted to fit into said clearance space, comprising a body 45 part, and infolding side edge portions; a frame carried by said bridge and at one end extended therebeyond under one of the table top sections; swinging links carrying the leaf-body, pivoted to said frame; an actuating lever carried by said extended end of the frame; and a connection between said lever and the leaf-body to elevate the leaf on its links when the lever is moved to one 50 position.
- 55 2. In an extension table, the combination of slidable semi-circular top sections, slide members secured to the top sections to provide between the slides and top sections a clearance space, a pedestal supporting the 60 slides, a leaf body of size to permit inclusion

thereof in said clearance space within the confines of the top when the latter is closed, parallel links connected to the said leaf portion and to a pedestal-carried part, said part extending between the slides toward the edge 65 of one of the table top sections, means upon said extended end of the said part to move said leaf portion upon said links into or out of the plane of the table-top, and edge sections pivoted to the edges of said leaf portion. 70

3. In an extension table, the combination of a set of three slide pairs; a bridge connecting the slides of the central pair; top sections carried by the inner and outer slide 75 pairs, adapted to meet when the table is closed and mounted above their slides to leave a central clearance space between the slides and the top sections; a leaf adapted to fit into said clearance space comprising a body portion and hinged edge portions; a frame having sides secured to the bridge between the slides and at one end extending therebeyond under one of the table top sections; guide strips secured to the leaf body 85 between the sides of the frame; swinging links connecting the said frame sides and guide strips and means on the frame extension for moving the leaf on its swinging-link connections. 90

4. In an extension table, the combination of a set of three slide pairs, a bridge connecting the slides of the central pair, top sections carried by the inner and outer slide pairs adapted to meet when the table is 95 closed and mounted above the slides to leave a central clearance space between the slides and the top sections, a leaf adapted to fit into said clearance space comprising a body portion and hinged edge portions, a frame 100 comprising two side members each secured upon the bridge parallel to the slides and extending beyond one edge of the bridge, and a cross member connecting said extended ends of the said members, guide 105 strips secured to the leaf body parallel to said members of the frame, swinging links connecting said side members of the frame and the respective guide strips of the leaf body, an actuating lever carried by said cross 110 member of the bridge-carried frame, and a connection between said lever and leaf body to move a leaf on its link by means of said lever.

In testimony whereof I hereunto set my hand in the presence of two witnesses.

EDWARD H. MERSMAN.
